MATTRESS CONSTRUCTION

David Micon, Los Angeles, Calif.

Application July 28, 1939, Serial No. 287,031

4 Claims. (Cl. 5—356)

This invention relates to the construction of mattresses, upholstered furniture, and the like, in which a padding material is covered by a fabric, and the fabric is anchored at points intermediate its edges.

A broad object of the invention is to provide a mattress and upholstery construction which is inexpensive and practicable, and at the same time provides for the anchoring of the cover material intermediate its edges without the use of tufts or buttons on the exterior surface of the fabric and without the production of holes in the fabric.

A more specific object of the invention is to provide a fabric for use in covering mattresses, upholstering furniture, etc., which fabric has anchor threads formed therein by which the fabric may be anchored intermediate its edges without extending tie cords through the fabric, and without the use of tufts, buttons or other projecting objects on the exposed surface of the fabric.

In mattresses and upholstered furniture it is necessary to connect the facing or covering material either to the cover material on the opposite side, in the case of mattresses, or to a base framework in the case of upholstered furniture, in order to retain the cover in place, compress the filling material, and prevent it from shifting. Cords are commonly employed as the connecting medium and in the usual construction are extended through the cover material, being either looped around a small portion of the cover material or knotted or secured to a button, or the like, to prevent the cord pulling through the cover material.

As pointed out in my prior Patent No. 1,771,185, issued July 22, 1930, constructions in which the tie cord extends through the cover material are objectionable because it necessarily involves forming openings in the cover which tend to become larger in use and permit entry of dirt and vermin into the interior of the mattress. In accordance with the teachings of my prior patent, such holes are eliminated by sewing anchor loops to the inner surface of the cover material, the tie cords engaging the loops instead of passing through the fabric.

The practice covered in my patent referred to has great advantages over the prior known practices but has the disadvantage that the sewing of the anchor loops to the cover material involves additional operations and expense to the mattress maker or upholsterer.

In accordance with the present invention, I

5 avoid the aforementioned defect of the process of my prior patent, while retaining all the advantages thereof, and at the same time obtain additional advantages, by providing a woven cover material having loops formed in special anchor threads of the fabric during the weaving thereof.

The invention will be more fully explained by describing in detail the particular fabric in accordance therewith and its application to a mattress, the description referring to the drawing in which:

Fig. 1 is a view of a section of fabric in accordance with the invention showing the right, or 15 outer, side of the material;

Fig. 2 is a view similar to Fig. 1, but showing the inner, or wrong, side of the material;

Fig. 3 is a detail view, showing a portion of the 20 underside of the fabric, greatly enlarged;

Fig. 4 is a detail sectional view, taken substantially in the plane IV—IV of Fig. 3; and

Fig. 5 is a detail sectional view through a mattress covered with a covering in accordance with the invention, and showing how the covering on 25 the two sides of the mattress are tied together.

Referring to Figs. 1, 2 and 3, the woven fabric therein depicted consists of a cloth made up of warp and woof threads having special or extra threads 10 extending in one direction of the fabric parallel to each other and in spaced apart relation. These threads 10 are interwoven with some, but not all, of the threads forming the cloth itself so that they lie substantially on the rear side of the fabric and are invisible from the front, or right, side. The particular fabric shown consists of warp threads 11 extending parallel to the threads 10 and weft threads 12 extending at right angles thereto. Therefore the special threads 10 extending in the direction of the warp 30 are interengaged by occasional weft threads 12.

In the particular construction shown, the threads 10 are engaged by approximately every sixth weft thread 12. As a result of the fact that each of the threads 10 is preferably relatively 35 heavy and is engaged by only a fraction of the weft threads, it extends as a ridge along the rear surface of the fabric and is substantially invisible from the front side of the fabric.

The thread 10, as previously indicated, is preferably relatively heavy in order to withstand the strains to which it is subjected, and in the particular construction shown is formed from a large number of smaller threads or laminations 13 which are simply bunched together and are not twisted. However, if desired, the thread 10 could

consist of a single cord or a large cord twisted from a large number of smaller cords.

At periodic intervals along the threads 10, slack is interposed therein to form loops 14 extending outwardly from the rear surface of the fabric. The loops 14 in the different threads 10 will ordinarily be spaced symmetrically so that they fall in rows extending both longitudinally and laterally of the fabric although this is not essential and sometimes it may be desirable to position the loops 14 differently along the different threads 10 so as to define special desired patterns.

As previously indicated, the loops 14 function to interconnect the fabric to tie cords and transmit the strain imposed by the tie cord to the fabric. Thus, as shown in Fig. 5, a portion of a mattress having an upper cover 16 and a lower cover 17, separated by filler material 18, are interconnected by tie cords 19 which are connected to the loops 14 formed in the cover material.

In order to firmly attach the threads 10 to the fabric, I find it advisable to employ additional threads 20 which extend at right angles to the threads 10 and parallel to the weft of the fabric, there being two of these threads 20 crossing the threads 10 adjacent the loops 14 therein. Thus, as best shown in Fig. 3, one of the threads 20 extends on one side of the loop 14 and the other thread 20 extends on the other side of the loop 14, the thread 20 in all instances extending across the threads 10 so as to restrain the threads 10 from pulling away from the fabric when force is applied to the loops 14. The threads 20 are connected to the fabric by being interwoven with a relatively small number of warp threads, whereby, like the threads 10, they extend as ridges along the rear face of the fabric and are substantially invisible from the right side of the fabric. In the particular construction shown, the threads 20 are engaged by approximately every sixth warp thread so that they are supported to substantially the same extent as are the threads 10.

As shown in the drawing, each thread 20 consists of two smaller filaments or threads lying parallel and untwisted. However these threads 20 may consist of single heavy twisted threads in some instances.

The fabric described is not only admirably suited to the purpose of the mattress-maker or upholsterer, but can be readily manufactured in present weaving establishments at relatively small expense over the plain fabrics which have no provision for anchoring the tie cords.

Although for the purpose of explaining the invention a specific embodiment thereof has been described in detail, it is to be understood that many changes can be made from the particular fabric disclosed without departing from the invention which is to be limited only to the extent set forth in the appended claims.

I claim:

1. A device of the type described comprising padding material having a cover fabric in overlying relation thereto and anchoring means in underlying relation thereto, an anchoring element incorporated in said cover fabric, and a tie cord interconnecting said anchoring means and said anchoring element, in which said anchoring element comprises: a textile loop woven into and forming an integral part of said cover and extending from the underside thereof, the two sides of said loop entering said cover fabric

at points so closely spaced to each other that there is negligible bulging of said cover between said points in response to strain on said loop.

2. A device as described in claim 1, in which 5 said cover fabric is composed of two sets of threads, one constituting a regular warp and the other a regular woof of the fabric, in which each thread of one set interengages substantially all the other threads of the other set, with additional anchoring threads extending parallel to the threads of one of said sets, but interengaging only a fraction of the threads of the other of said sets and being distributed substantially on one side only of the fabric, said anchoring threads having a slack portion therein defining an anchor loop on one side of the fabric, said anchor loop constituting such special anchoring element.

3. A device as described in claim 1, having a 20 plurality of anchoring elements, and in which said cover fabric consists of a woven fabric composed of two sets of threads, one constituting the regular warp and the other the regular woof of the fabric, each thread of one set interengaging 25 substantially every thread of the other set, and additional anchor threads including a first auxiliary set of threads extending parallel to the threads of one of said first mentioned sets but interengaging only a fraction of the threads of 30 the other of said first mentioned set and being distributed substantially entirely on one side only of the fabric, said first auxiliary threads having slack portions therein at intervals therealong defining anchoring loops, and a second set 35 of auxiliary threads disposed in pairs close together and the two threads of each pair bridging each thread of said first auxiliary set at each end of each of the said loops therein, said second auxiliary threads interengaging only a fraction 40 of the threads of one of said first mentioned sets of threads and being distributed substantially entirely on one side only of the fabric, said anchoring loops constituting said special anchoring elements.

4. A device as described in claim 1, having a 45 plurality of anchoring elements, and in which said cover fabric consists of a woven fabric composed of two sets of threads, one constituting the regular warp and the other the regular woof 50 of the fabric, each thread of one set interengaging substantially every thread of the other set, and additional anchor threads including a first auxiliary set of threads extending parallel to the threads of one of said first mentioned sets but interengaging only a fraction of the threads 55 of the other of said first mentioned set and being distributed substantially entirely on one side only of the fabric, said first auxiliary threads having slack portions therein at intervals therealong defining anchoring loops, and a second set of auxiliary threads disposed in pairs close together and the two threads of each pair bridging each thread of said first auxiliary set at each end of each of the said loops therein, said second auxiliary threads interengaging only a fraction of the threads of one of said first mentioned sets of threads and being distributed substantially entirely on one side only of the fabric, said anchoring loops constituting said special anchoring 60 elements, and said first auxiliary threads being substantially heavier and stronger than the regular warp and woof threads of the fabric.
